UNITED STATES PATENT OFFICE.

GEORGE A. XANDER, OF HAMBURG, AND JOHN G. XANDER, OF READING,
PENNSYLVANIA.

METHOD OF SEWING.

SPECIFICATION forming part of Letters Patent No. 399,310, dated March 12, 1889.

Application filed May 28, 1888. Serial No. 275,297. (No model.)

To all whom it may concern:

Be it known that we, GEORGE A. XANDER, residing at Hamburg, and JOHN G. XANDER, residing at Reading, both in the county of Berks and State of Pennsylvania, have invented certain new and useful Improvements in the Method of Stitching; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of this invention is to form a lock-stitch adapted more particularly to fasten together materials which it is necessary to secure only at points a greater or less distance apart. The principle of the stitch used is the same as that involved in the well-known "glove-hitch;" and our invention consists in a new manner of forming it. A machine by means of which this may be done is therefore not shown or described; but we merely indicate the movements required to form the stitch in a preferred manner.

Figure 1 represents the well-known "glove-hitch" or "waterman's knot." Fig. 2 shows our separate lock-stitch before tightening, clearly indicating the general principle of its construction.

Fig. 3 shows the successive loops required in making the stitch by the preferred method illustrated in different stages in Figs. 4 to 11, each of these loops, as well as their different threads, being indicated by corresponding letters and figures throughout. N represents an eye-pointed needle, and R a suitable form of rotary hook with point R' and "cast-off" R². B, C, and D represent the first, second, and third loops in the order in which they are formed, while 1 and 2 are the first and second threads of the first loop, 3 and 4 of the second, and 5 and 6 of the third. H and T represent hooks which are adapted to seize and move the loops, as indicated.

Fig. 4 represents the first loop formed and caught upon the point of the rotary hook in the usual manner, the material moved ahead, and the needle ready for its second descent. Thread 1 is in the rear.

Fig. 5 shows the first loop twisted by the rotation of the hook R², which may be of the usual shape to effect this. The needle is ready for its second ascent and the point R' of the rotary hook is preparing to enter the second loop. Thread 1 is in front.

Fig. 6 shows the position of the first and second loops reversed, the second, C, having been passed through the first by the rotation 60 of the hook R, while the first is preparing to escape from the cast-off R², and the hook H is in position to catch it. Threads 1 and 4 are in front.

Fig. 7 shows the first loop caught by the hook 65 H, which is in the act of pulling it through the second loop. The latter is still on the point end of the rotary hook, and threads 1 and 4 remain in front.

Fig. 8 shows the second loop twisted, bringing thread 3 in front. The first loop has been pulled through it and is still on the hook H, thread 1 being bent around thread 4 and its end about to escape from the material. Thread 2 is twisted around thread 3. The needle has descended and the point R' of the rotary hook 75 is about to take up the third loop.

Fig. 9 shows the first loop destroyed, thread 1 being freed from the material and as an extension of thread 2 thrown forward. This is 80 the natural position of thread 2, it having been previously twisted or bent around thread 3 of the second loop, whereas it now passes straight through said loop. The third loop is on the rotary hook and being drawn through 85 the second, the latter being held by the cast-off R².

Fig. 10 shows the second loop freed from the cast-off R², the third loop well drawn through it, and its rear thread, 5, engaged by a hook, 90 T, a sudden movement of which is adapted to tighten up the second loop, the tension of the main thread being sufficient to prevent it from being pulled down.

Fig. 11 shows the knot or stitch tightened up, the thread 2 passing through the second or central loop in one direction, while the threads 5 and 6 pass through it in the opposite direction, the second loop holding them snug against the under side of the material. 100 The hook T, the movement of which has thus tightened the knot, keeps the thread 5

stretched until a suitable knife or shears is brought into play and it is cut at a point, K, thus permitting the end thread, 6, to be withdrawn and remain with the needle while the material is moved onward to the desired point for another stitch, leaving the one just made substantially as shown in Fig. 2, except that in the latter it is not shown as tightened up.

- It will be seen that this method of stitching 10 will form a very secure fastening in all cases where it is not necessary that a continuous line of stitching should be used. A succession of stitches may be thus made, each knotted and entirely independent of the others, 15 and any desired distance apart. The main feature of the glove-hitch is maintained—namely, the tendency to tighten the knot on pulling either end of the thread. The general method of using it, however, as herein set forth, and as shown in Fig. 2, is substantially different from the usual method shown in Fig. 20 1, and we do not confine our invention to the preferred method of forming it by machine, as particularly described herein.
- 25 What we claim as new, and desire to secure by Letters Patent, is as follows:

1. The method of forming separate lock-stitches, consisting in passing a thread through the material at three points, so as to form a 30 central loop and pulling both ends of the

thread through said loop, substantially as set forth.

2. The method of forming separate lock-stitches, consisting in passing a thread through the material from one side thereof in a series 35 of three loops and pulling both ends of thread through the central loop, substantially as set forth.

3. The method of stitching herein set forth, 40 which consists in forming two loops, reversing their position, pulling the end of the thread which forms the first loop through the second, forming a third loop, passing it through the second, and tightening the knot.

4. The method herein set forth of forming 45 a series of lock-stitches, which consists in forming two loops, reversing their position, pulling the end of the thread which forms the first loop through the second, forming a third loop, passing it through the second, tightening 50 the knot, cutting the thread, and moving the material into position for the next stitch.

In testimony whereof we affix our signatures in presence of two witnesses.

GEO. A. XANDER.

Corrections in Letters Patent No. 399,310.

It is hereby certified that in Letters Patent No. 399,310, granted March 12, 1889, upon the application of George A. Xander, of Hamburg, and John G. Xander, of Reading, Pennsylvania, for an improvement in "Method of Sewing," errors appear in the printed specification requiring the following correction: In lines 21 and 27-8 page 1, and line 16, page 2, the words "glove-hitch" should read *clove-hitch*; and that the Letters Patent should be read with these corrections therein to make it conform to the record of the case in the Patent Office.

Signed, countersigned, and sealed this 19th day of March, A. D. 1889.

[SEAL.]

H. L. MULDROW,

First Assistant Secretary of the Interior.

Countersigned:

BENTON J. HALL,

Commissioner of Patents.
